P. C. CHAMBELLAN.
CARPET.

No. 21,089.

Patented Sept. 29, 1891.

UNITED STATES PATENT OFFICE.

PIERRE CHARLES CHAMBELLAN, OF WEST HOBOKEN, NEW JERSEY, ASSIGNOR
TO THE BIGELOW CARPET COMPANY, OF CLINTON, MASSACHUSETTS.

DESIGN FOR A CARPET.

SPECIFICATION forming part of Design No. 21,089, dated September 29, 1891.

Application filed September 7, 1891. Serial No. 405,034. Term of patent 3½ years.

To all whom it may concern:

Be it known that I, PIERRE CHARLES CHAMBELLAN, a citizen of the French Republic, residing at West Hoboken, in the county of Hudson, State of New Jersey, have invented a new and original Design for Carpets, of which the following is a specification, reference being had to the accompanying photograph, which forms a part of the same.

- 10 The invention relates to a design to be worked into or upon surfaces, such as carpets or similar fabrics; and it consists in the novel configuration and grouping of figures herein specifically shown and claimed.
- 15 The accompanying photograph is a face view of a carpet, showing my new design.

My design consists of the body A and the border B. The body A is composed of scroll-shaped stems ornamented with leaf forms and having intermingling sprays of leaf and flower forms. The border B has an inner ornamental margin, a main portion composed of scroll-shaped stems ornamented with leaf forms and having intermingling sprays of leaf and flower forms, and an outer margin containing various ornamental somewhat diamond-shaped figures and conventionalized scroll-shaped leaf forms. 25

What I claim as new, and desire to secure by Letters Patent, is— 30

- 1. The design for carpets, consisting of the body A, substantially as shown.
- 2. The design for carpets, consisting of the border B, substantially as shown.
- 3. The design for carpets, consisting of the body A and the border B, substantially as shown. 35

PIERRE CHARLES CHAMBELLAN.
